(57) **CLAIM**

The ornamental design for a cannula pad, as shown and described.

DESCRIPTION

FIG. 1 is a bottom perspective view of a cannula pad embodying our new design;

FIG. 2 is a bottom view thereof;

FIG. 3 is a top view thereof;

FIG. 4 is a first side view thereof;

FIG. 5 is a second side view thereof;

FIG. 6 is a front side view thereof; and,

FIG. 7 is a rear side view thereof.

Broken lines are used to illustrate features of the cannula pad which form no part of the claimed design. Broken lines showing perforation lines along the top and the bottom of the cannula pad form no part of the claimed design.
